UNITED STATES PATENT OFFICE.

JESSE C. TEMPLE, OF HATTIESBURG, MISSISSIPPI.

HIGH-PRESSURE PAINTING DEVICE.

Application filed December 28, 1923. Serial No. 683,238.

To all whom it may concern:

Be it known that I, JESSE C. TEMPLE, a citizen of the United States, residing at Hattiesburg, in the county of Forrest, State 5 of Mississippi, have invented certain new and useful Improvements in High-Pressure Painting Devices; and I do hereby declare the following to be a full, clear, and exact description of the invention, such as will 10 enable others skilled in the art to which it appertains to make and use the same.

This invention relates to new and useful improvements in coating devices, and particularly to devices for coating surfaces with 15 paint, or like fluid materials.

One object of the invention is to provide a device of this character wherein the discharging nozzle is capable of easy and quick angular movement, so that the material may 20 be directed against either horizontal or vertical surfaces.

Another object is to provide such a nozzle as will remain in adjusted position until a change is desired, thus rendering the coating 25 of the surface simple and effective.

Another object is to provide a paint spraying device wherein the paint and air conduits are disposed in concentric relation throughout the greater portion of their 30 length, thereby rendering the grasping and holding of the device more easy and comfortable to the workman.

A further object is to provide a nozzle for 35 a device of this character wherein the stream of compressed air is directed against the head of the column of paint, with the result that the paint is completely broken up and discharged through the orifice of the nozzle in a fine spray.

40 Other objects and advantages will be apparent from the following description when taken in connection with the accompanying drawing.

In the drawing:

45 Figure 1 is an elevation of a paint spraying device made in accordance with the invention, only a portion of the tank being shown.

Figure 2 is an enlarged longitudinal sectional view through the paint and air conduits, and the nozzle and conduit sections, 50 said conduits being broken.

Figure 3 is a modification of the device.

55 Referring particularly to the accompanying drawing, 10 represents a tank which is adapted to contain the paint, and into which

leads a pipe 11, for conducting compressed air from a suitable compressor (not shown) into the tank, to urge the paint from the tank.

A pipe 12, is connected with the tank, by means of a flexible hose 13, and between the pipe 12 and the hose 13 is arranged a cut off valve 14. A three way coupling 15 is also disposed in the pipe beyond the valve, one branch 16 of which is connected with a valve 17, and said valve is connected with the tank by means of a hose 18, this latter connection with the tank being for the purpose of conducting compressed air from said tank. Extending longitudinally and centrally within the pipe 12 is a small pipe 19, one end extending into and being tightly fitted within the branch 16. On the other end of the pipe 12 there is a three way coupling 20, and into the branch 21 thereof is tightly fitted the other end of the small pipe 19. To the other end of the coupling 20 is connected an L-shaped pipe 22, and in the end of the outer leg of this pipe is fitted a threaded nipple 23, said nipple having a head 24 on its other end. Slidably and rotatably disposed on the nipple, beneath the head 24, is an externally threaded collar 25 which is screwed into the outer end of the vertical leg 26 of the T-coupling 27. In one side of the branches of the coupling 27 is screwed a nipple 28, while a nipple 29 is screwed into the other branch, this nipple being the discharge nozzle of the device, and from which the paint is directed onto the surface to be painted. Engaged on the nipple 23, adjacent the leg of the pipe 22, is a nut 30, and encircling the nipple, between the nut and the collar 25, is a coil spring 31 which is arranged to be tensioned by the nut 30, whereby to press the collar firmly against the shoulder of the head 24, and produce a tight joint for preventing the escape of air or paint. Connecting the nipple 28 and the branch 21 is a flexible pipe or hose 32, by means of which the compressed air may flow from the pipe 19 through the T-coupling 27, and the nozzle 29, across the upper end of the column of paint which issues from the orifice of the head 24, into the coupling, by way of the pipes 12 and 22.

When properly screwed onto the collar 25, the coupling 27 will easily rotate with said collar, about the stem or nipple 23. The tension of the spring 31, which is regulated by the movement of the nut 30 on the stem

or nipple 23, holds the collar 25 in firm frictional engagement with the shoulder of the head 24, thus permitting the coupling 27 to remain in any of its rotatably adjusted positions. The adjustment of the coupling is accomplished by pressing the nozzle 29 against the surface to be painted, so as to cause the nozzle to swing to the desired angle. Thus, the operator, when standing 10 in one position, may apply paint to a vertical surface, or to an upper or lower horizontal surface. The paint is forced from the tank by the pressure of the compressed air, and issues from the central orifice of the 15 head 24, into the T-coupling, where the head of the column of paint is struck by the air issuing from the adjacent end of the pipe 19, and broken into a fine spray which escapes from the orifice of the nozzle 29 onto 20 the surface to be painted.

Should the surface to be painted be dirty, or covered with cobwebs, or the like, the valve 14, is closed while the valve 17 remains open, the operator then moving the 25 nozzle 29 over the surface so as to blow the foreign matter from the surface. Upon opening the valve 14, the paint will be forced through the pipe 12, and out of the nozzle 29.

The concentric arrangement of the air and 30 paint conduits provides for a simple and convenient handle for the operator to grasp while directing the nozzle over the surface to be painted.

In Figure 3 there is shown a modification 35 of the invention, which has been designed particularly for painting the opposite sides of railway rails and for use in destroying grass and weeds along the railway, by spraying this vegetation with a liquid prepared 40 for the purpose. In this embodiment of my invention I employ two or more nozzles which are so mounted as to permit their outlets to be directed towards each other, so as to operate on the opposite sides of a rail, 45 or away from each other so as to spray the vegetation and the railway ties.

In the modification illustrated in Figure 3, the outer end of the pipe 12' is provided with suitable coupling 33, which receives the 50 ends of the branch pipes 34. Upon the outer end of each of these branch pipes is an elbow 35, to each of which is connected a spray nozzle including the elements 23', 30', 55 31', 32', etc., similar to the parts described in connection with the form illustrated in Figures 1 and 2.

When using my invention in connection with railways a device such as illustrated in Figure 3 is mounted at each side of a car 60 carrying a tank to receive the liquid and air, each group of nozzles being connected with this tank, as herein described and arranged,

with their outlets at opposite sides of a rail. When paint is being applied, the outlets are directed towards each other to operate on 65 opposite sides of the rail. When used for the destruction of vegetation, the nozzles of each group are directed away from each other so as to distribute creosote, or another suitable preparation, upon the vegetation 70 and the ties. In this way the vegetation is destroyed and the ties are preserved.

What is claimed is:

1. A painting device including a paint conduit, couplings at opposite ends of the 75 conduit provided with branches, an air conduit disposed centrally within the paint conduit and having its ends fitted in the said branches, a discharge nozzle mounted on one end of the paint conduit, and a flexible conduit between the nozzle and the adjacent end 80 of the air conduit.

2. In a painting device, a paint and air conduit, a threaded nipple on one end of the paint conduit, said nipple having a head, a 85 nozzle including a mixing chamber receiving said head, connection between the air conduit and the mixing chamber, a threaded collar on the nipple bearing against the head, a spring on the nipple bearing against 90 the collar, and means on the nipple for varying the tension of the spring.

3. In a device of the class described, liquid and air conduits, a T-coupling mounted on the liquid conduit, and nozzles carried by 95 the coupling and arranged to be directed toward each other and away from each other.

4. A painting device, including a source of supply, a conduit leading from said source, spraying nozzles connected with the 100 conduit and means whereby the nozzles may be adjusted to operate selectively in converging or diverging directions.

5. A painting device, including a source of supply, a conduit leading from said 105 source, a plurality of spraying nozzles and means connecting the nozzles with the conduit whereby said nozzles may be selectively adjusted to operate in different directions.

6. A painting device including paint and 110 air conduits, a T-coupling, a discharge nozzle in one branch of the coupling, an air injector nozzle in the other branch of the coupling, a ring secured within the leg of the coupling, a paint nozzle rotatable within the 115 ring and having a shoulder seated on the ring within the leg, the other end of the paint nozzle being secured within the paint conduit, a nut on the paint nozzle, and a spring on the paint nozzle between the ring 120 and the nut.

In testimony whereof, I affix my signature.

JESSE C. TEMPLE.
